(57) **CLAIM**

The ornamental design for an apparatus to control fluid flow
through a tube, as shown and described.

DESCRIPTION

FIG. 1 is a front, top, and right-side perspective view of an
apparatus to control fluid flow through a tube, showing our
new design;

FIG. 2 is a front elevational view thereof;

FIG. 3 is a right side elevational view thereof;

FIG. 4 is a back elevational view thereof;

FIG. 5 is a left-side elevational view thereof;

FIG. 6 is a bottom plan view thereof; and,

FIG. 7 is a top plan view thereof.

The broken lines in the drawings depict portions of the
apparatus to control fluid flow through a tube that form no
part of the claimed design.

The dash-dot broken lines define the bounds of the claimed
design and form no part thereof.
